PROCESS OF MAKING ACETYLENE FROM
HIGHER SATURATED HYDROCARBONS

Paul Askenasy, Karlsruhe, Germany, Carlo Rossetti, Yverdon, Switzerland, and Jenö Tausz, Karlsruhe, Germany, assignors to the firm Society of Chemical Industry in Basle, Basel, Switzerland

Application May 26, 1931, Serial No. 540,186
In Germany June 6, 1930

2 Claims. (Cl. 204—31)

The present invention relates to a process of making acetylene from higher saturated hydrocarbons by means of the electric arc.

It is known that acetylene can be made by 5 passing a higher saturated gaseous, vaporized or atomized hydrocarbon through an electric arc.

We have made the surprising discovery that a very considerable proportion of the energy of the electric arc can be utilized for the production of 10 acetylene and at the same time the concentration of the acetylene in the gases which leave the arc raised to a very substantial value by increasing the energy density of an extremely short electric arc of low tension with respect to at least 15 one of the electrodes to a value in the neighbourhood of that at which a loss of substance of the electrode exceeding the normal wear and tear commences.

By the term "higher saturated hydrocarbons" 20 we understand: hydrocarbons of the paraffin or olefin series, such as methane, ethane, ethylene and homologues thereof, in pure form or as mixtures with other gases, as for instance earth gas, cracking gases, coke oven gas, coal gas or other 25 gases resulting from distillation of carbonaceous material, or constituents of cracking gases, coke oven gases, coal gas, or of other gases resulting from the distillation of carbonaceous material, further hydrocarbons resulting from the working 30 up of petroleum, such as benzine, gas oil, fuel oil and the like, further aromatic hydrocarbons, such as benzene, toluene, naphthalene and the like. Of course also mixtures of the above mentioned hydrocarbons may be employed. Further one 35 may also employ hydrocarbons which already contain a certain amount of acetylene, for instance the gases which remain after separating the bulk of the acetylene from the mixture resulting from the process described below. The 40 presence of foreign gases, as for instance hydrogen, nitrogen, precious gases is not detrimental so long as they do not attain too high a concentration. If nitrogen be present, a certain amount of hydrocyanic acid is formed besides acetylene, 45 which former may easily be eliminated by absorption in an alkaline medium.

It has proved advantageous to perform this process in a cyclic manner such as is described in Patent No. 1,547,714.

50 An apparatus suitable for cyclic operation is illustrated diagrammatically in the accompanying drawing.

K is a continuous tubular system constructed, for example, of iron, in which the gases or vapors 55 to be treated are caused to circulate by means of

the blower G in the direction indicated by the arrow. Fresh hydrocarbon, for instance methane, ethylene or the like, to replace that which is decomposed in the electric arc, is introduced by way of the inlet E. A is an electrode suitably 60 insulated from the system K and constructed in the form of a tube through which a part of the gases circulating in the system is withdrawn from the arc. L is a counter-electrode.

The following example illustrates the invention:—

In the apparatus above described there was used as one electrode a carbon rod of 30 mm. diameter and as the other electrode a carbon tube of internal diameter 14 mm. and wall thickness 70 10.5 mm. The distance between the electrodes, which depends to a certain extent on the velocity with which the gases are circulated, was about 2 mm. A direct current electric arc was struck between the electrodes, the potential being about 75 38 volts and the current strength about 350 amperes. The system K was filled with methane which was caused to circulate with a high velocity by means of the blower G. 17 cubic metres of gas were withdrawn per hour by way of the electrode A, a corresponding quantity of fresh gas being introduced through the inlet E. The gas mixture withdrawn from the system had the following composition:—

	Per cent by volume
C_2H_2	9.55
C_2H_4	1.10
CH_4	49.35
H_2	40.00

It will be seen from the above figures that an expenditure of energy of 6.8 kilowatt-hours was required for the production of 1 kilo of acetylene. The temperature of the gases circulating in the system K was about 100° C., but may also be substantially higher. In general it was found to be advantageous to maintain the temperature of the circulating gases at a fixed value and to counteract any substantial rise in the temperature by suitable cooling. The very hot gas leaving the system by way of the electrode A was separately cooled. The pressure within the system K exceeded the external atmospheric pressure by about 0.15 atmosphere.

When the energy density of the electric arc was increased above that corresponding with the above example, a point was quickly reached at which a small loss of substance of the electrode could be detected; the utilization of the energy at this point was equally good. When, on the other 105 110

hand, the energy density was decreased the gradual diminution in the utilization of the energy and at the same time of the concentration of the acetylene in the withdrawn gases was observed.

5 For example, when the potential of the arc was about 35 volts and the current about 180 amperes, 15 kilowatt-hours were required for the production of one kilo of acetylene; when the potential of the arc was about 30 volts and the current about 100 amperes, about 23 kilowatt-hours were required.

In carrying out the invention attention must be paid to the following points. When one of the variable conditions is altered (pressure, temperature, energy density, speed of circulation of the gases, etc.), then a new optimum must be found by suitable variation of the other conditions; this, however, may be quickly carried out. For example, in order to attain the high utilization of 10 energy and satisfactory concentration of the gases in acetylene in an apparatus having other dimensions one may proceed empirically as follows:

The energy density is first determined at which a loss of substance of the electrode exceeding the 15 normal wear and tear commences and is maintained in the neighbourhood of this point whilst the gas is caused to circulate with a high velocity. Thereupon the inlet E is connected with a source of the gas which is to be admitted (gas container) 20 and increasing quantities of gas are withdrawn by way of the electrode A until they show the desired concentration in acetylene. The rate at which gas is withdrawn from the system is then further increased until the desired concentration 25 of acetylene begins to fall substantially. In this manner the optimum conditions are found and may then be maintained, the velocity of the circulating gases in the system K being, if necessary, varied in order to repress, as far as possible, the 30 formation of soot. The conditions given in the example, that is to say energy density (correspondingly the cross-sectional area of the electrodes), and the rate of withdrawal of gas at a concentration of 10 per cent of acetylene in the 35 withdrawn gas, show how it is possible easily and quickly to adjust the variable operating conditions to produce economically favorable results.

In certain circumstances it may be desirable to use electrodes containing additions, the vaporizable portions of which may mix with the stream of gas; in this respect there come particularly into question substances which influence the electrical conductivity in the zone of the electric arc.

When there is used a vaporized or atomized 50 hydrocarbon the circulatory system must be so constructed that there is always a sufficient quantity of hydrocarbon in circulation, that is to say one must operate in a heated circulatory system. For this purpose the whole system is advantageously heated by means of a steam jacket or otherwise to a temperature at which the hydrocarbon introduced to the system has a sufficient high vapor tension. When a mixture of hydrocarbons is used the temperature need only be such 55 that a sufficiently large fraction of the hydro-

carbons has the required vapor tension. In the latter case, at the boiling point of one fraction of the hydrocarbon mixture the remaining fractions, which are still at a temperature below their boiling points, are atomized to such a degree that the hydrocarbon mixture is to a sufficient extent in the desired fine state of subdivision. It is frequently possible to maintain a sufficiently high temperature by merely insulating the system against loss of heat.

80 It has proved especially useful to generate the electric arc with direct current, which latter may be of low tension.

85 The process may be conducted at atmospheric pressure or at a pressure higher or lower than atmospheric pressure; operation under a raised pressure is to be recommended since it involves an improvement in the utilization of the energy.

90 The invention permits the production of acetylene by means of the electric arc with a surprisingly small consumption of energy and simultaneously a remarkably high concentration of 95 acetylene in the gases.

95 Having regard to the low cost of the parent materials, disturbance of the process owing to 100 the simultaneous formation of soot and hydrogen is insignificant; thus, when operating in the manner described in the example there was produced at the most 200 grams of soot for each kilo of acetylene.

105 If there is used as an addition to the electrodes, as hereinbefore referred to, a substance such as lime whose carbide or carbide components are vaporized, it is advantageous to give only one electrode a high carbide content or to use only one 110 carbide electrode, whilst the other is wholly or in greater part a carbon electrode the loss of substance of which may then serve as an indication of the electrical energy density to be used in accordance with the invention.

115 There may be used more than one tubular electrode, which may serve both for the introduction of gases into the system and for the withdrawal of gases from the system.

120 What we claim is:—

1. In the manufacture of acetylene by treating higher saturated hydrocarbons in the electric arc, the step which consists in maintaining the energy density of an electric arc of 2 millimeters length and of low tension with respect to at least one of 125 the electrodes in the neighbourhood of that at which a loss of substance exceeding the normal wear and tear commences.

2. Process according to claim 1, wherein the materials under reaction are made to circulate 130 with great velocity, fresh gases being simultaneously introduced at one point of the cycle and the reaction gases being removed at another point of the cycle, the speed of the current of the gases streaming into and out of the cycle being 135 kept lower than the speed of the reacting gases in the cycle.
